UNITED STATES PATENT OFFICE.

HORACE S. LOOMIS, OF AUBURN, NEW YORK.

DUMPING-WAGON.

SPECIFICATION forming part of Letters Patent No. 288,823, dated November 20, 1883.

Application filed August 4, 1883. (No model.)

To all whom it may concern:

Be it known that I, H. S. LOOMIS, a citizen of the United States, residing at Auburn, in the county of Cayuga and State of New York, 5 have invented certain new and useful Improvements in Dumping-Wagons, of which the following is a specification, reference being had therein to the accompanying drawings.

This invention has for its object to provide 10 a wagon from which the load may be conveniently dumped, as more fully hereinafter specified. These objects I attain by the means illustrated in the accompanying drawings, in which—

15 Figure 1 represents a top view of my improved wagon; Fig. 2, a bottom view of the same, and Fig. 3 a central vertical transverse section of the wagon.

The letter A indicates the frame or truck of 20 the wagon, mounted upon the axles B, which are provided with the usual wheels, C. The front and rear ends of the said frame or truck are provided with vertical standards, which have studs D, to which the parts of the wagon- 25 body are pivoted, as more fully hereinafter specified.

The wagon-body is semicircular in cross- 30 section, and is divided longitudinally, the parts being pivoted to the studs before mentioned, as indicated by the letter E.

At each side of the frame A are journaled, in suitable bearings, the bars F, which have

fastened to them the chains G, which are also fastened to the lower edges of the respective parts of the body, the bars F being provided 35 with cranks, whereby they may be rotated to wind the chains and elevate the parts of the body to dump the load.

The wagon-body, midway between the ends, rests upon rollers H, journaled in suitable 40 bearings in the curved frame I.

I reserve the right to slightly vary the construction of the parts without departing from the spirit of my invention.

Having thus described my invention, what 45 I claim, and desire to secure by Letters Patent, is—

1. The combination, with the wagon-frame, of the wagon-body divided longitudinally into two parts, which are pivoted to vertical 50 standards at each end of the frame, at the top thereof, and the bars and elevating-chains, all arranged to operate substantially as specified.

2. The combination, with the wagon-body, divided and pivoted as described, of the sup- 55 porting-rollers, upon which the central portion of the body rests, substantially as specified.

In testimony whereof I affix my signature in presence of two witnesses.

HORACE S. LOOMIS.
